UNITED STATES PATENT OFFICE.

DAVID D. GORDON, OF CHICAGO, ILLINOIS, ASSIGNOR, BY MESNE ASSIGNMENTS, TO
McGILL MANUFACTURING COMPANY, OF VALPARAISO, INDIANA, A CORPORATION
OF INDIANA.

SWITCH-OPERATING APPARATUS.

Application filed April 20, 1918, Serial No. 229,743. Renewed October 8, 1923.

To all whom it may concern:

Be it known that I, DAVID D. GORDON, a citizen of the United States, residing at Chicago, in the county of Cook and State of Illinois, have invented a certain new and useful Improvement in Switch-Operating Apparatus, of which the following is a full, clear, concise, and exact description, reference being had to the accompanying drawings, forming a part of this specification.

My invention relates to switch operating apparatus and has to do more particularly with switch mechanism pertaining to lamp sockets one of the objects being to provide an improved and simplified device of this character and one in which the operating key or lever is removably secured to the switch mechanism so that it may be taken off for refinishing or readily interchanged. Another feature is the provision of an improved and flexible connection between the operating lever and the switch movement.

In devices of this character the socket and switch operating key or lever may be carried in stock separated from the enclosing shell and cap, and where the lever is metal, as in the present case, it is advantageous to have it readily removable so that levers of different finish may be interchanged to correspond with the finish on the enclosing shell and cap. Also in most of the standard shells, key slots are provided through which the operating key or lever of the switch movement projects. In the present form of device this lever rests upon a seat which protrudes from the socket and shell slot, acting as a guide to prevent relative rotary movement of the shell and socket. This seat being preferably fixed to the movement, and the movement being interchangeable with different shells and caps, it is very desirable that the seat be practically invisible so that the exposed part may have a standard finish, whereby due to the small portion visible it may be used with shells of different finishes. It is also very desirable to have a readily removable lever which may be taken off for refinishing or levers of different finish readily interchanged. These various features are pres-

ent in my invention. However, for a better understanding of my invention reference is to be had to the accompanying drawing in which—

Fig. 1 is a longitudinal cross-section 55 through the preferred form of switch mechanism with the switch closed;

Fig. 2 is a cross-section along the line 2—2 of Fig. 1;

Fig. 3 is a view showing the switch movement in its open position;

Fig. 4 is a sectional view along the line 4—4 of Fig. 1 but reduced somewhat in size;

Fig. 5 is a perspective view of the switch movement mounting frame;

Fig. 6 is a perspective view of two of the switch parts;

Fig. 7 is so called horseshoe terminal which is connected to the threaded shell of the socket; and

Fig. 8 is a detail view of the connector inside the lever.

Fig. 9 is a side view of the shell removed from the cap and showing the slot for receiving the operating lever or key.

Referring now more particularly to the preferred form of my invention, it comprises an insulation base preferably in the form of an upper porcelain block 10 and lower porcelain block 11 which are recessed at their adjoining faces to enclose the switch movement. A shell 12 slotted to receive the key and an insulating lining 13 are also provided with a cap 14 having a recessed skirt 16 adapted to receive a correspondingly shaped flange 17 on the collapsible end of the shell 12. It is of course, to be understood that my invention is by no means limited to any particular type of shell but the form shown is merely for the purpose of illustration.

A threaded socket shell 18 is suitably attached to the lower insulation block 11 preferably by means of rivets 19, 20 (Fig. 4) which extend through a horseshoe terminal plate 21 carrying a binding post or terminal 22 projecting upwardly along a slot 23 in the peripheral face of block 11, and carries a terminal screw 24 to which one of the current conductors is attached.

Now as to the switch movement, this includes a frame A, having a pair of threaded ears 25, 26 by means of which the frame is attached to the block 11 through the medium of screws 27. This frame A also carries a pair of side arms 28 having switch arm pivot pins 29 upon which the switch arm 30 is supported. This switch arm 30 which is adapted to close the circuit through the lamp 10 is preferably insulated from the rest of the mechanism and therefore I provide insulating collars 31, which surround the pivot pins 29 and extend through the switch arm 30, so that this switch arm is insulated from the 15 frame A. The switch arm 30 has a reciprocating operating movement so as to open and close the circuit by a snap action, and to this end I connect this arm 30 to an operating key or lever B through a helical spring 32, intermediate link 33, and pull link 34. In order to fully insulate the switch arm 30 from the rest of the movement, the spring 32 is connected to the arm 30 through the 20 medium of a T shaped insulating piece 30^a, the cross-head of which extends along the outermost face of the arm 30 while its other portion is connected with the spring 32. The other end of the spring 32 hooks over the yoke of the intermediate link 33 which link 30 has a pair of lugs 35 which hook into the slotted ends 36 of the pull link 34. It will 25 be noted that the intermediate link 33 has upper and lower hook extensions 37, and 38 respectively which are adapted to engage the ends 39, 40 respectively of the frame A, so that this intermediate link 33 will pivot about the axis 39 or axis 40, (according to its position) whenever the operating link 34 is pulled toward the left. (Figs. 1 and 3).

40 The switch arm 30 is adapted to close and open the circuit through the lamp and to this end I provide contacts 41 and 42, contact 41 being connected to the binding post or terminal 43 which is attached to the insulating block 11 and carries a terminal screw 44. The switch contact 42 is connected to the center lamp-terminal 45, the parts 42 and 45 being preferably an integral punching. The contact portion 42 extends through a 45 slot in the block 11 into the path of the switch arm 30 and connects with the plate portion which is bent back to form the yielding terminal 45. In order to insulate the contact element 42, 45 from the adjacent threaded sleeve contact elements 18, 21, a ridge 46 projects from the face of the insulating block 11 and around the contact element 42, 45, having a peculiar shape as shown in Fig. 4.

50 The circuit through the device extends from the line terminal 43 through switch contacts 41, switch arm 30, switch contact 42 and its integrally connected center lamp contact 45, the filament of the lamp to the threaded shell 18, horseshoe terminal 21 and

line terminal 22 to the other line conductor. This circuit, of course, is made and broken through the operation of the switch arm 30.

The operating lever mechanism B for controlling the switch movement consists preferably of a lever 50 which rests upon a flanged seat or rest 51 which is fixed to the frame A so as to protrude from the shell and with the flange of the seat acting as a guide for the shell 12 when the socket is inserted therein. That is, when the socket is inserted in the shell 12 the wall of the shell is guided between the laterally projecting portions of the seat 51 and the insulation 13 or insulating blocks 10 and 11. A boss 52 extends from the flange of the seat 51 and acts as a guide for the lever 50, the boss 52 extending into a recessed portion of the lever 50 so as to always effect a concentric seating of these parts. This boss and flange 80 construction of the seat, also provides a universal pivot for the lever when tilted as indicated in Fig. 3.

In order to connect lever 50 with the movement I provide a flexible link in the 90 form of a standard ball chain consisting of a plurality of balls 54 connected by wire links, the inner ball 54 being hooked into the yoke end of the link 34 while the outer ball 54 is carried in the end of a sleeve 55. 95 This sleeve is drawn in at its ends so as to leave a small opening to permit the wire connection between the balls to extend therethrough, and also contains a longitudinal slot 56 so that the ball may be inserted 100 through the central opening 57 and then slid along to the end of the sleeve. The outer end of the sleeve 55 is adapted to carry an operating extension in the form of a pull chain 58 or an ordinary cord if desired. 105 This sleeve 55 is held in the lever 50 by means of a screw 59, the sleeve being slidable in the lever 50 and therefore may be adjusted so as to take up inaccuracies of manufacture or adjustment, it simply being necessary to slide the lever 50 over the sleeve 55 until it rests upon the seat 51, and then take up the set screw 59.

I preferably employ a link 54 which is slightly stronger than the outer pull chain 115 58 so in case of a breakage, it will occur outside the shell and thus obviate the necessity of repairing parts inside the device.

One of the important advantages of my improved construction is that the fixed seat 120 which protrudes from the shell is visible only to such a slight extent that a standard finish thereof may be employed such as will go readily with any finish of shell and lever. Furthermore, the lever being readily removable, it is, of course, interchangeable and thus it is easy to provide levers and shells of a corresponding finish. Also, the lever may be readily removed for refinishing. The seat, however, which is important 125 130

should be fixed to the frame so as to prevent tampering with the parts and thus throwing the movement out of adjustment, is exposed to such a small extent as to be almost invisible, so far as consideration of its finish is concerned.

Operation.

Now as to the operation of the switch mechanism, when the switch in its closed position as shown in Fig. 1, lever 50, which is universally operable, may be tilted in any direction, that is, up or down or sideways, or it may be pulled straight out, thereby drawing link 34 toward the left. The intermediate link 33 therefore, is rotated about its hooked pivot 37, 39 so that the left end moves upwardly against the tension of spring 32. This upward movement continues by reason of the pull upon lever 50 until the portion to which the spring 32 is attached has passed above a line between the pivot 29 and the fastening 35 of the switch arm 30. At this time the spring 32 immediately acts to draw the switch arm 30 from its circuit position across contacts 41, 42 by a quick snap action. This operation has brought the lower hook 38 of the intermediate link 33 to a point above the lower extremity 40 of the frame A and back of its extremity, that is with the lever 50 still fully operated. However, as soon as the pressure or pull upon lever 50 is released, it is drawn back to its seat by the action of the spring 32 which pulls the intermediate link 33 toward the right, its lower point 38 riding along on the inner surface of 40, until it reaches the extremity at which time it drops down into the position indicated in Fig. 3 and the continued restoring movement of the lever 50 permits a further movement of the hook 38 until there is a slight clearance between the extremity of the portion 40 as indicated between parts 37 and 39 of Fig. 1. The switch is now open and in order to close it the lever 50 is again operated resulting in a reverse operation of the switch arm 30, the action in this case being the same as in its opening movement, that is a quick snap closing operation.

For the purpose of illustrating my invention I have shown a preferred form but it is to be understood that I contemplate applying it in other ways than that shown and therefore I do not desire to be limited to the exact structure shown and described but aim to cover all that which comes within the spirit and scope of the appended claims.

Having thus described my invention, what I claim as new and desire to secure by Letters Patent is:

1. Switching mechanism for lamp sockets comprising a shell a switch movement having a frame carrying a fixed seat protruding from the shell, and an externally secured

readily removable universal lever tiltably resting on the seat and connected with the switch movement.

2. Switching mechanism comprising a cover, a switch movement having a frame carrying a fixed seat protruding from the cover, a lever universally tiltably resting upon the seat whereby the seat acts as a fulcrum for the lever, and an externally readily disconnectible connection between the lever and movement.

3. The combination with a switch mechanism of a bearing member a hollow operating lever for said mechanism having an end thereof engaging said bearing member and a connection extending from said lever to said mechanism comprising a retaining clip mounted in the interior of said lever, and a pull connection connected at one end to the switch mechanism and at the other end to said clip.

4. Switching mechanism for lamp sockets comprising a slotted shell, a switch movement having a frame projecting through the slot in the shell, a flanged seat secured to the outer end of the projecting portion and a tilttable lever seating around the edge of the seat flange, said lever being removably and universally connected to the switch movement through said seat.

5. Switching mechanism comprising a switch-movement having a frame, a seat on the frame, a universally tilttable lever resting upon the seat, and an intermediately yieldable connection extending from the lever through the seat to the movement.

6. Switching mechanism comprising a switch-movement having a frame, a seat on the frame, a universally tilttable lever resting upon the seat, and an intermediately yieldable connection extending from the lever through the seat to the movement, said lever being readily removably attached to said connection.

7. Switching mechanism comprising a switch movement having a frame, a seat on the frame, a tilttable lever resting upon the seat whereby the seat acts as a fulcrum for the lever, and a connection between the lever and movement to which the lever is adjustably and readily removably secured.

8. Switching mechanism for lamp sockets comprising a slotted shell, a switch movement having a frame, a flanged seat fixedly secured to the frame, the flange of the seat together with the frame acting as a guide for the insertion of the movement into the shell.

9. Switching mechanism for lamp sockets comprising a slotted shell, a switch movement having a frame, a flanged seat fixedly secured to the frame, and protruding from the slot in the shell, said seat and frame acting as a guide for the insertion of the movement into the shell, and said

frame acting to prevent relative rotation of the frame and shell.

10. Switching mechanism comprising a switch-movement, a seat, a tiltable lever resting against the seat, a sleeve removably held inside the lever, and means for connecting a movement link at one end of the sleeve and a pull-chain to the other end of the sleeve.

10 11. The combination with a switch mechanism of a hollow operating lever for said mechanism and means connecting said lever with said mechanism comprising a retaining clip mounted in the interior of said lever, a securing member mounted in said lever and engaging said clip and a pull connection extending endwise from said lever and connected at one end to the switch mechanism and at the other end to said clip.

20 12. The combination with a switch mechanism of a hollow operating lever for said mechanism and a connection extending

longitudinally thru said lever to said mechanism comprising a retaining clip mounted lengthwise in the hollow of said lever, a securing member mounted in said lever and extending into the hollow thereof to hold said clip in said lever, and a connection secured at one end to the switch mechanism and at the other end to said clip.

25

13. The combination with a switch mechanism of an operating lever for said mechanism having a longitudinally extending bore therein and a connection extending from said lever to said mechanism comprising a retaining clip mounted in said bore and extending longitudinally of said lever, and a pull connection extending from one end of said lever and connected at one end to the switch mechanism and at the other 40 end to said clip.

35

In witness whereof, I hereunto subscribe my name this 5th day of April, A. D. 1918.

DAVID D. GORDON.
